DRINKING GLASS

Nicholas P. Angelakos, Brooklyn, N.Y., assignor to Lancaster Colony Corporation, a corporation of Delaware

Filed June 6, 1969, Ser. No. 17,550

Term of patent 14 years

Int. Cl. D7—01

U.S. Cl. D36—8

FIG. 1

FIG. 4

FIG. 2

FIG. 3

FIG. 1 is a side elevational view of a drinking glass showing my new design;

FIG. 2 is a bottom view;

FIG. 3 is a top view; and

FIG. 4 is a fragmentary cross-sectional view along a radius of the glass.

I claim:

The ornamental design for a drinking glass, substantially as shown.
